UNITED STATES PATENT OFFICE.

HERBERT GROVE DORSEY, OF ITHACA, NEW YORK.

ELECTRIC INDICATING SYSTEM FOR RAILWAYS.

No. 892,814.

Specification of Letters Patent.

Patented July 7, 1908.

Application filed November 5, 1907. Serial No. 400,781.

To all whom it may concern:

Be it known that I, HERBERT GROVE DORSEY, a citizen of the United States, and a resident of Ithaca, in the county of Tompkins and State of New York, have invented a new and Improved Electric Indicating System for Railways, of which the following is a full, clear, and exact description.

This invention relates to certain improvements in systems employed on railways, so constructed that the engineer or other employee on one train may ascertain the presence of an obstruction to the free passage of the train and whether said obstruction comprises an open switch, a broken rail, or a second train, that is, if such obstruction is within a predetermined distance from the train. In my improved system the train-man is enabled not only to ascertain the presence of such an obstruction, but in case it is a moving train, he may also ascertain the direction in which this second train is moving and the speed of the same. The same principle may be employed for ascertaining from a station, the instant a train comes within a predetermined distance from said station and the direction from which said train is coming and the rate at which it is traveling.

Reference is to be had to the accompanying drawings, forming a part of this specification, in which similar characters of reference indicate corresponding parts in both the figures, and in which

Figure 1 illustrates diagrammatically the wiring and arrangement of parts going to make up my improved system, and showing the mechanism of two separate cars on the same track and going in the same direction, but at different speeds; and Fig. 2 illustrates diagrammatically the approach of a train provided with my improved system toward an open switch.

The mechanism employed in carrying out my invention is very simple. A pair of conductors parallel the road-bed, and each train carries a mechanism engaging with each of the conductors. One of these conductors, 10, is insulated from the ground and from the other conductor, and may comprise a third rail, a trolley wire, or any other suitable construction. This conductor is subdivided into sections of any desired length, depending upon the range to be given to the instruments carried by the trains, the sections be-

ing preferably from a half mile to a mile long. If desired, the several sections may overlap at their ends or may be arranged in duplicate with the brakes in one conductor intermediate the ends of the sections of the other conductor, whereby each train may at all times communicate for a considerable distance in front and behind. The other conductor may also be insulated from the ground, but is preferably continuous. In the simplest form of construction, one of the rails of the railway track 11 is employed as this conductor.

Each train carries mechanism for generating an electric current, the terminals of said generator being connected to the two separate conductors, there being no current flowing unless the two conductors be short-circuited by a second train or an obstruction. As illustrated diagrammatically, each car carries a dynamo 12, geared to the car wheel 13, so that it rotates at a speed directly proportional to the speed of the train. The dynamo may be of any suitable type, and generate either a direct, alternate, or pulsating current, the nature of the current being comparatively unimportant. The generator is reversible, that is, when rotated in the reverse direction it operates equally as well but the poles are reversed and the current flows in the other direction. One lead 14 from a brush of the dynamo is connected to the broken conductor 10, while the other lead 15 is connected through the car axle and car wheel to the other conductor or car track 11. In one of these leads or connections, I insert an instrument 16, constructed along the same lines as an ammeter, but preferably calibrated to read in distance per unit of time, preferably, in miles per hour. Shunted across the dynamo between the sections 14 and 15, is a second instrument 17, somewhat similar to the instrument 16 but constructed more on the lines of a voltmeter. This instrument is also calibrated to read in distance per unit of time. In connection with the dynamo circuit, a separate relay circuit is employed, the latter including a battery 18, an audible or visible signal 19, and a circuit closer 20, preferably forming the armature of an electromagnet 21 disposed in the generator circuit. In the leads or connections 14, behind the instrument 17, is preferably a reversing switch 22, whereby when the engine or car carrying the mechan-

ism is turned around to travel in the opposite direction, the direction of current may be reversed.

During the normal running of the train having indicating mechanism constructed in accordance with my invention, the indicator 17 will show the speed at which the train is running, as it is shunted across the dynamo and the latter is geared to the car wheel. The instrument 16 will have a zero reading, inasmuch as no current can flow therethrough so long as there is no short circuit between the conductors 10 and 11. If any obstruction occurs on the track, operating to short circuit between the two conductors, the current can then readily flow from the dynamo through one of the leads and one of the conductors to the obstruction, and thence back through the other conductor and the other lead to the dynamo. The resistance to the passage of the current through the conductors is so small compared to the resistance of the portion of the system carried on the train; that the instruments 16 and 17 will read substantially the same and almost if not identically. The passage of the current through the electromagnet 21 closes the relay circuit and operates the signal 19, to call the attention of the engineer or other trainman to the fact that a short circuit between the conductors 10 and 11 exists somewhere along the length of the particular section of the conductor 10 which the train is passing over. If the reading on the instruments 16 and 17 is substantially the same, the trainman will know that the obstruction is not a moving train, but that it is either an open switch, a stationary train, or a board or other object placed across the conductors to signal the train to stop.

If there are two trains on the same section and both moving, they both will be delivering current to the conductors and if both of the trains are moving in the same direction, the positive pole of each will communicate with the same conductor. If the two trains are going at identically the same speed, each dynamo will counteract the effect of the other and the indicators 16 of the two trains will both show the same as though they were on a clear track. If either train is going faster than the other, the dynamo of that train will overbalance the effect of the other dynamo, and a current will flow, the strength of which will be dependent upon the difference in speeds. The reading on the faster train will be plus to the extent of this difference, and the reading on the slower train will be minus to the same extent. As the indicator 17 of each train is unaffected by the presence of the other train, its reading will show the speed of the particular train carrying it, independent of the presence of any other train. If the two trains are traveling in opposite directions, that is, toward or from

each other, the positive pole of each dynamo will be connected to different conductors and the two dynamos will be acting in series. Thus the amount of current set through the circuit will be dependent upon the sum of the speeds of the two trains and on each train the indicator 16 will show this sum. It is thus evident that the engineer can at any time tell to a certainty, whether any other train is on the same block with him, whether or not that train is moving, and if moving, the direction and speed of such movement.

The reversing switch 22 is not operated when a train merely reverses its direction of motion, that is, when it backs up. So long as the train remains headed in the same direction, the switch 22 remains stationary, but if the engine or other part of the train carrying the mechanism is turned around on a turn-table or goes around a loop to face in the opposite direction, then the reversing lever is thrown to send the current in the reverse direction, so that all trains traveling in one direction will deliver current to one of the conductors, while all trains traveling in the reverse direction will deliver current to the other conductor. In each circuit, there may be provided, if desired, a switch by which the current may be broken at will, or, if desired, a reversing switch may be employed for this purpose. The engineer upon noting on the indicator 16 that a second train is on his block, may by operating the switch, make and break the current to send a message to the other train, the message being read by the other engineer by the variations in the position of the indicator 16 of said second train. Thus the message may be sent in the dots and dashes of the Morse code or any other code desired. At each switch, the construction is such that the opening of the switch places the conductor 10 in electrical contact with the conductor 11, whereby as soon as the train reaches the opposite end of the block from said switch, the engineer noting on the indicator 16 the closed circuit condition, takes the proper precaution to avoid an accident.

As illustrated in Fig. 2, one of the rails forming a conductor, is provided with a spring contact 23, which when the straightaway track is clear is out of engagement with the conductor 10, but as soon as the switch is thrown to the position illustrated, a link 24 permits the closing of the circuit between the conductor 10 and spring 23. Each of the stations along the track may be provided with mechanism similar to that carried by the cars, or may contain simply a mechanism for closing the circuit between the two conductors, said circuit-closing means including a switch and an indicator. The stationman by closing the switch indicates to the approaching train that the road is not clear, or by intermittently opening and clos-

ing the switch may send any desired signal to the engineer.

By constructing the generators to deliver an alternate or pulsating current and putting condensers into the circuit, the mechanism may be used with electric railways having track and trolley, and the signals sent over the same conductors as is the current for operating the trains. Preferably at bridges the construction is such that upon opening the bridge or the breaking or washing away of the same, the contact between the two conductors will be closed to warn the approaching engineers.

Having thus described my invention, I claim as new and desire to secure by Letters Patent:

1. An electrical indicating system for rail-ways, including a pair of conductors par-

alleling the road-bed, means carried by each train for generating the current in direct proportion to the speed of the train, and having connections engaging with said conductors, and an indicator in one of said connections, the operation of which is dependent upon the speed of a second train similarly equipped and having connections with the same conductors.

2. An electrical indicating system for rail-ways, including a pair of conductors par-

alleling the road-bed, means carried by each train for generating the current in direct proportion to the speed of the train and having connections engaging with said conductors,

and means in one of said connections serving

to indicate the speed of a second train simi-

larly equipped and having connections with

the same conductors.

3. An electrical indicating system for rail-

ways, including a pair of conductors par-

alleling the road-bed, means carried by each

train for generating the current in direct pro-

portion to the speed of the train and having

connections engaging with said conductors,

and means in one of said connections serving

to indicate the direction of travel of a second

train similarly equipped and having connec-

tions with the same conductors.

4. An electrical indicating system for rail-

ways, including a pair of conductors par-

alleling the road-bed, means carried by each

train for generating the current in direct pro-

portion to the speed of the train and having

connections engaging with said conductors,

and means in one of said connections serving

to indicate the speed and direction of travel

of a second train similarly equipped and hav-

ing connections with the same conductors.

5. An electrical indicating system for rail-

ways, including a pair of conductors par-

alleling the road-bed, means carried by each

train for generating the current in direct pro-

portion to the speed of the train and having connections engaging with said conductors and an indicator in one of said connections, the operation of which is dependent upon the speeds and directions of travel of a train carrying said indicator and of a train similarly equipped and having connections with the same conductors.

6. An electrical indicating system for rail-ways, including a pair of conductors par-

alleling the road-bed, means carried by

train for generating a current in direct pro-

portion to the speed of a train and having

connections engaging with said conductors,

a relay in one of said connections, includ-

ing a signal, and an indicator in one of said

connections, the operation of which is depen-

dent upon the closing of the circuit between

conductors.

7. An electrical indicating system for rail-

ways, including a pair of conductors par-

alleling the road-bed, means carried by

train for generating the current in direct pro-

portion to the speed of the train and having

connections engaging with said conductors,

an indicator showing the speed of

train, and a second indicator, the opera-

tion of which is dependent upon the speed

second train similarly equipped and hav-

ing connections with the same conductors.

8. An electrical indicating system for rail-

ways, including a pair of conductors par-

alleling the road-bed, an electric gene-

ator carried by the train and operated from

running gear thereof, whereby the cur-

rent generated is in proportion to the speed o

train, connections from said generator to

conductors, and an indicator reading

distance per unit of time in one of said connec-

tions and operated only upon the

circuiting of one of said conductors.

9. An electrical indicating system for rail-

ways, including a pair of conductors par-

alleling the road-bed, an electric gene-

ator carried by the train and operated from

running gear thereof, whereby the cur-

rent generated is in proportion to the speed o

train, connections from said generator to

conductors, an indicator reading in dist-

per unit of time in one of said connec-

tions and operated only upon the short circu-

it of one of said conductors, and mecha-

nism adapted to short circuit said conductors;

the operation of a railroad switch along

track.

In testimony whereof I have signed

name to this specification in the presen-

two subscribing witnesses.
